UNITED STATES PATENT OFFICE

LEE S. GATY, OF COLUMBUS, OHIO

METHOD OF AND APPARATUS FOR MAKING HOLES IN THE GROUND

Application filed March 26, 1931. Serial No. 525,408.

This invention relates to a method of and apparatus for making holes in the ground to receive posts or poles of various sorts.

Heretofore such holes have been dug or bored with a great expenditure of time and money and the object of the present invention is to make a better hole than can be dug or bored and do the job much more quickly and cheaply than by any means or method heretofore employed as far as I am aware.

Other objects will appear from the disclosure.

The invention is embodied in the example herein shown and described, the feature of novelty being finally claimed.

In the accompanying drawings—

Figure 1 is a side elevation, with some small parts omitted, of one form of the apparatus according to the invention showing the same as carried by a boom the latter being broken off.

Fig. 2 is an elevation looking toward the right hand side of Fig. 1.

Fig. 3 is a plan view looking at the lower end of Fig. 2.

Fig. 4 is a view, on a larger scale, partly in section and partly broken out of the earth penetrating tool and the pneumatic hammer removed from its frame.

Fig. 5 is a side view of the upper end of the tool.

Fig. 6 is a plan view of the upper end of the tool.

Fig. 7 is a side view like Fig. 1 of a modification.

Fig. 8 is a side view of the tool with parts omitted, shown in Fig. 7, removed from the hammer and dipper stick.

Fig. 9 is a detail in plan view of the upper end of the modified tool.

Fig. 10 is a detail on a larger scale showing the swivel connecting means between the tool and stick.

Fig. 11 is a view illustrating a post hole and the effect on the walls thereof produced by the tool herein described for forming the same.

Referring first to the views, Figs. 1 to 6 inclusive, the character 12 thereon designates the earth penetrating tool which generally is

a slightly tapered hollow body terminating at its business end in a conical nose 12^a. Said nose 12^a is secured to the lower end of the body 12 by means of a tapered pin 13 that can be driven out to permit removal for sharpening or replacement of the nose. The nose is preferably made of a very hard steel so that it can penetrate and break up some rocks. The tool thus constructed is the male counterpart of the hole to be formed.

At its upper end the tool is provided with perforated ears 14 by means of which the tool can be hung to slotted ears 15 on the lower end of the cylinder 16 of the pneumatically operated hammer 17. The slots are unalined and the connection permits the feed of the tool and also a rise slightly in detaching the tool from the ground. The pneumatic hammer is of the ordinary kind and needs no particular description herein.

At its upper end the tool has fixed therewith a projecting collar 18 notched at diametrically opposite sides to be engaged by strips 20 fixed on the backs of U-bars 19 that, with cross pieces 20^a at the top, constitute a frame for containing and vertically guiding the tool and hammer when in operation.

The lower ends of said frame bars have pivoted to them as at 21 a rebound or tool ejecting device composed of two parallel rings 22 and 23 with a series of coil springs 24 between them. The upper ring 23 is provided diametrically with opposed notches 23^a to engage the U-shaped bars 19 of the guiding frame.

The springs 24 are each held in position between the rings by means of a threaded bolt 25 secured by a jam nut to the lower ring, the upper ring being held yieldingly down on the springs by nuts 26. The perforations for the bolts 25 are made large enough to permit the movement of the upper ring toward the lower ring so that the springs can be compressed. The central openings of the rings 22 and 23 permit the tool, in operation, to pass through them and when the tool has been driven into the earth to nearly the full length thereof and when the collar 18 strikes the upper ring 23 the springs 24 are compressed with the effect that the tool is lifted

from contact with the walls of the hole after which the apparatus may be easily hoisted away from the ground.

Between the ears on the lower end of the hammer cylinder and resting on the upper end of the tool is a loose anvil 27 to receive the blows of the hammer.

In the views thus far described the hole forming apparatus is hung by means of a cable 29^a passing over a pulley in the end of a boom 29 carried on any suitable vehicle (not shown) so that the hole forming apparatus can be transported to the place of the job and the tool lowered to the point on the surface of the ground where the hole is to be made. The pipe for supplying compressed air to operate the hammer is shown at 16^a.

Referring now to Figs. 7 to 10 inclusive, the apparatus is shown as adapted for use in connection with the parts of a power shovel. In this application the guiding frame, including the frame members 19, before referred to, is dispensed with and the dipper stick 30 of the power shovel used. The rebound or ejector device is secured near the upper end of the tool.

The tool is swivelly connected with the end of the dipper stick by means of a fork or yoke 31 having its tangs perforated to engage pins 32 on the head of the tool; and said fork is provided with a shank 33 that can turn in bearings in plates 34-35 on the end of the dipper stick. The said shank is secured by a suitable pin 36 in its said bearings.

The pneumatic hammer is supplied with operating compressed air through pipe 37 and the hole forming apparatus is supported for raising and lowering and swinging by a cable 38 running over a pulley 39 on boom 40, such as before described.

In Fig. 11 is depicted the effect of making a post hole in the ground with and according to the method involved herein. The heavy darkened lines and graduation of such lines near and beyond the surfaces of the walls of the hole suggest the hard packing at and near the surface of such walls. The advantage of this packing is that when the tool is removed, the hole is left clear of obstructions and ready to receive the post to be placed and secured therein. The hole will usually be made of slightly larger diameter than the post so that if desired grout or other materials can be filled into the space around the foot of the post and tamped to hold the post in erect position and preserve the material thereof at its foot.

The forms and proportions of the parts can be changed without departing from the gist of the invention as claimed.

What I claim is:

1. The method of forming a hole in the earth consisting in driving a tool of the form of the hole into the locus of the hole and

thereby compressing the earth from the locus of the hole into the earth bounding such locus and yieldingly resisting the operation of the driving tool when the hole is nearing completion.

2. In apparatus for forming a hole in the earth for a post or the like, an earth penetrating tool having a tapered body portion and a pointed lower end, a projecting shoulder at its upper end and retracting spring means carried at the upper end of said tool and means for driving said tool into the earth.

3. In apparatus for forming a hole in the earth for a post or the like, an earth penetrating tool having a body portion and a pointed lower end, and means for driving said tool into the earth and spring means associated with said tool for detaching the same from the walls of the hole when the same is substantially formed.

4. In apparatus for forming a hole in the earth for a post or the like, an earth penetrating tool having a tapered body portion and a pointed end, and means for driving said tool into the earth and spring means acting on said tool for detaching the same from the walls of the hole when the same is substantially formed.

5. In apparatus for forming a hole in the earth for a post or the like, an earth penetrating tool having a body portion and a pointed lower end, means for driving said tool into the earth, and spring means located at the upper end of the tool and actuated by the tool when the hole is nearly formed, said spring means tending to detach the tool from the earth when the hole is substantially completed.

6. In apparatus for forming a hole in the earth for a post hole or the like, an earth penetrating tool having a body portion and a pointed lower end, said penetrating tool being a male counterpart of the form of the hole to be made, and means for driving said tool into the earth, a frame in which said tool is reciprocated, said frame carrying spring means located therein to retract the tool when the hole is nearly completed.
